SPARK CONTROL

Raymond Hufford, Anderson, Ind.

Application October 28, 1938, Serial No. 237,415

6 Claims. (Cl. 137—153)

This invention relates to apparatus for transferring the suction in the intake system of a vehicle engine (including a carburetor) to the apparatus and to and from the carburetor and from and to a governor for the engine and vice versa, and in association with a spark control for the engine.

No claim is made to the broad combination of an engine arrangement including a fuel control, a spark control and governor means, all for control of the engine arrangement and howsoever operated.

One chief object of the present invention is to secure proper and sensitive correlation between such engine control elements.

Another chief object of the invention consists in the transfer of suction and pressure so that the apparatus, herein disclosed, is normally inoperative for spark control operation, but upon attainment of critical engine speed becomes effective for such control and thereby resulting in more efficient engine operation at such critical speed.

The chief feature of the invention consists in the accomplishment of both objects by the use of mechanism which is much simpler than that heretofore employed for comparable purposes and which further is distinguished therefrom in that the engine suction is transferred and controlled relative to spark control apparatus in a novel manner as herein after pointed out.

Other objects and features will be pointed out more fully hereinafter.

The full nature of the invention will be understood from the accompanying drawings and the following description and claims:

In the drawings—

Fig. 1 is an elevational view of a portion of an engine intake system with the invention applied thereto, said system including a suction governor, the invention being shown in section, and the spark control apparatus per se being omitted, parts being shown in wide open or normal running position.

Fig. 2 is a similar view of the parts shown in Fig. 1, but illustrated in the controlled speed position.

Figs. 3 to 6 illustrate a modified and simplified form of the invention and Fig. 3 is a plan view thereof.

Fig. 4 is an elevational view looking at the left hand end of the device shown in Fig. 3.

Fig. 5 is a similar view looking at the lower side while Fig. 6 is a similar view looking at the right hand end of the device shown in Fig. 3.

Figs. 7 to 10 illustrate another and simplified form of the invention. Figs. 7 to 10 are similar respectively to Figs. 3 to 6 of this third form of the invention.

5 In the drawings 10 indicates an anchorage flange of a carburetor 11, the body portion having an intake passage 12 therethrough in which is mounted on shaft 13 the throttle valve 14. The remainder of the carburetor mechanism has been intentionally omitted for clearness. Flange 15 of the carburetor is adapted for governor structure connection.

The governor structure, illustrated more or less diagrammatically herein includes the body portion 16 with registering intake passage 17 therein. In said passage upon shaft 18 is mounted governor controlled valve 19.

For a more complete understanding of the instant governor structure, shown by way of example only, reference is had to the co-pending application of Raymond Hufford, entitled "Suction governor," Serial No. 236,395 and filed October 22, 1938.

15 The remainder of the engine intake system is omitted for clearness, as well as the specific spark control apparatus per se.

Reference will now be had to the apparatus embodied specifically in the present invention. Passage 11, in predetermined relation to valve 14, includes a port 20 (compare Figs. 1 and 2). In registration therewith, and externally thereof, is a conduit anchoring boss 21 to which is connected a relatively large conduit 22, the opposite end of which is connected at 23 to housing 24, herein shown carried by housing 16 of the governor structure.

Leading from the housing 24 at 25 is a relatively large conduit 26 which is intended to be connected to a spark control device, not shown, nor is there illustrated herein the spark control operating means responsive to the pressure in conduit 26. These are omitted for clearness. This operating means may be of piston or diaphragm type. In the body portion 24 is a bore or cylinder chamber 27 reduced as at 28 at its closed end and enlarged as at 29 at its open end to receive a press fitted head or disk 30. Slidably mounted therein is a piston valve 31 having at one end a reduced portion 32 and at the opposite end reduced portion 33. The end 33 and the main body portion 31 is apertured at 34 to nest spring 35.

Chamber 23a in portion 23 includes port 36 and passage 37, the latter communicating with the cylinder 27 near the capped end. Chamber

25a in portion 25 includes a port 38 in alignment with port 36. The reduction 32 on piston 31 insures direct communication of the capped end of cylinder 27 with passage 12 at all times.

Communication between ports 36 and 38, and therefore chambers 23a and 25a, is controlled by valve 31. In Fig. 1 there is no such communication. In Fig. 2 these ports freely communicate.

The reduced end 28 of the cylinder 27, in which end of spring 35 is seated, communicates by passages 39 and 40 and passage 40a with chamber 25a. Passage 40 communicates by port 41 and connection 42 with port 43 leading into passage 17 and is always subject to manifold suction.

It is noted that port 20 has communication with the intake system on the remote side of valve 14 with respect to the governor valve 19 and port 41 has similar communication with the intake system on the remote side of valve 19. In Fig. 1 throttle valve 14 is shown in open position and governor valve 19 is shown almost closed. In Fig. 2 governor valve 19 is shown almost full open position and throttle valve 14 is shown in closed position and extending therebeyond. Thus port 20 is on the carburetor side of the unit when valve 14 is closed and port 41 is on the engine side of valve 19 at all times.

The term "remote" is used in opposition to the term "adjacent" with reference to both valves 14 and 19 and the intake passage portion therebetween.

Piston 31 is, therefore, a vacuum operated member subjected to manifold pressure on the engine side of the governor valve on one end at all times, the other end being subjected to atmospheric side of the carburetor valve when the carburetor valve is at or near a closed position and on the engine side at all other positions. The communication between the cylinder and the engine side of the governor valve has sufficient capacity to compensate for leakage between the cylinder and piston. The same vacuum in conduit 26 thus is maintained as exists in the engine manifold. This conduit is open at all times.

It is quite apparent that a diaphragm operated valve may readily be substituted for the piston operated valve 31-32-33 without departing from the broader features of the invention.

It is to be understood that communication 36-38 is of greater area than the communication 43-42 and 40 for bleeding purposes, thus rendering the spark control inoperative when the valve 19 is in open position, as shown in Fig. 2. The force of spring 35 is insufficient to force piston 31 to the right until such time as the engine speed attained has produced a drop in manifold pressure. Then spring 35 becomes effective and interrupts the communication 36-38. Upon such action occurring conduit 26 (and, therefore, the spark control apparatus) is subjected to the existing vacuum in the engine or manifold.

This invention, therefore, is characterized by having one communication 43, 42, 40 and 26 open at all times, and the control is rendered inoperative at predetermined speeds by having both communications open. Also observe that the small passage from the engine side of the governor valve is negatived by the large passage to the carburetor passage bleeding off the former when both are in communication.

From the foregoing description of the parts and critical limits as recited hereinbefore, the operation of the control herein disclosed will be readily apparent.

In Figs. 3 to 10 there is illustrated two simpli-

fied forms of the invention and ones which are not directly associated with a governor mechanism but which may be employed when no governor is employed on an automotive engine or which when employed with a governor permits governor removal without spark control removal and the like.

Figs. 3 to 6 illustrate a form which is interposed in a windshield operating vacuum line. In these figures numerals of the one hundred series similar to those of primary series employed in Figs. 1 and 2 designate like or similar.

Herein conduit 122 connects with the carburetor and is subject to the vacuum pull on the downstream side of the control valve. Conduit 126 leads to the immediate spark control device, not shown herein. Conduit 142 is connected to one end of an interrupted vacuum line connecting the engine to a windshield wiper or comparable vacuum operable device. Conduit A connects to the other and adjacent end of the interrupted vacuum line.

The valve mechanism employed herein is identical to that illustrated in Figs. 1 and 2 and operates in like manner.

In Figs. 7 to 10 there is illustrated a somewhat similar simplified form of the invention. Herein numerals of the two hundred series of numbers indicate like or similar parts found in Figs. 1 and 2 and Figs. 3 to 6 indicated by numerals of the primary series and increased by one hundred, respectively.

In this form of the invention conduit 242 is connected to the intake manifold on the engine side of the throttle or downstream thereof. Conduit 222 is similarly connected to the carburetor while conduit 226 is connected to the spark control device, which together with the carburetor, and intake manifold is omitted for clearness.

The valve mechanism is the same as that illustrated in Figs. 1 and 2 and operates in like manner.

The foregoing three forms of the invention illustrate three different applications of the invention and the methods of utilizing the same under different circumstances.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A differential pressure control including three passages, one adapted for connection to a device for fluid control of that device, another adapted for connection to a variable source of suction other than that device, and a third adapted for connection to a source of pressure at least as great as that to which the second passage is to be connected, a body having a valve bore therein, a valve in said bore, independent passages connecting each of the first and third passages to the bore and juxta-positioned relative to each other for communication when said valve is in one position in the bore, said valve being normally constrained toward another position to prevent said last mentioned communication, means interposed between the valve and second mentioned passage for subjection to the

source of suction at all times, and another passage providing restricted communication between the first and second mentioned passages for subjecting the first mentioned passage to the source of suction at all times, and intermittently to the third mentioned passage in accordance with valve operation responsive to variation in the source of suction when the suction force is greater than the restraint and when so connected overcoming the effect of the restricted suction application to the first mentioned passage.

2. A differential pressure control device including a valve body having a bore therein, a passage, a second passage communicating at one end with the bore at all times and at the opposite end with the first mentioned passage, a third passage communicating with the bore, valve means in the bore normally constrained to prevent first and third mentioned passage communication, a fourth passage communicating with the bore in opposed relation to the valve positioning and arranged to connect the bore at all times to a source of suction, and a restricted communication between the third and fourth mentioned passages for the purpose described, valve movement being responsive to pressure-suction application thereto.

3. A device as defined by claim 1 characterized by the valve means being of piston type.

4. A device as defined by claim 1 characterized by the addition of spring means operatively associated with the valve means for normally constraining same as described.

5. A device as defined by claim 1 characterized by the addition of spring means operatively associated with the valve means for normally constraining same as described, the valve means being of piston type.

6. In a differential pressure operable control for a conduit adapted for connection to a pressure operable device for operation thereof by pressure variation in the conduit, the combination of a passage having continuous but restricted communication with the conduit and connected to a source of variable suction for continuously applying suction to the device, valve means, a valve controlled passage connected to 15 a source of variable pressure, the pressure being at least as great as the suction, said valve controlled passage communicating with said conduit in one position of the valve means and when in that communicating position, the pressure varying the continuous but variable suction effect in said conduit, means normally constraining said valve means into a position wherein the valve controlled passage does not communicate with the conduit, and means connecting said valve means to the sources of suction and pressure for continuously subjecting the valve means to the differential effect thereof, variation of the differential effect in excess of the constraint operating said valve means for effecting the aforesaid communication to offset the suction in said conduit.

RAYMOND HUFFORD.
